UNITED STATES PATENT OFFICE.

KARL RÖGER, OF LONDON, ENGLAND.

MATRIX-SETTING AND LINE-CASTING MACHINE.

Application filed December 5, 1927, Serial No. 237,942, and in Germany January 22, 1925.

This invention is for improvements in matrix-setting and line-casting machines and relates to means whereby matrices at a dissimilar level in a line of matrices are brought 5 to a similar level during their progress through the machine.

The invention is particularly applicable to matrix-setting and line-casting machines of the type wherein matrices are accommodated 10 in a casting-carriage at different levels by means of the ears of the matrices co-operating with a number of parallel slots at different vertical levels in the casting-carriage, and wherein the casting-carriage at its outermost position from the mould is located 15 horizontally opposite the lowermost position of an elevator. The second elevator is arranged to accommodate the matrices at a single level and transfer them to the distributor. 20

It is known to provide devices for transferring the matrices from the casting-carriage to the elevator, whereby the matrices are brought to a single level. In these 25 known devices the lower matrices are placed level with those on the higher level, or conversely those on the high level are placed level with the lowermost matrices. It has been proposed to transfer matrices from one 30 level to the other with the aid of converging slots, but since the only method was to raise the lower matrices to the level of those lying above them, or conversely, the slope of the inclined slots had to extend over the full 35 difference between the levels at which the matrices are set to form a line. The inclined slots were therefore comparatively steep, with the consequence that the matrices easily jammed when passing over these slots, with 40 rapid wear as the result. Endeavours to avoid steepness led to unduly long slots which unnecessarily increased the dimensions of the machine.

According to this invention there is provided in or for a matrix-setting and line-casting machine a matrix aligning device through which the matrices are traversed from a number of tracks (e. g. parallel tracks) comprising a guideway having a 45 number of guide slots therein corresponding to the number of tracks, which slots are so spaced apart at one end of the guideway as to co-operate with the tracks and converge together at or towards the other end of the guideway at a junction point intermediate of, preferably midway between the outer

most lines along which the matrices travel when leaving the said tracks. In a matrix-setting and line-casting machine of the type referred to, the aligning device may be disposed between the uppermost position of the casting-carriage and the lowermost position of the elevator and the guide slots are spaced apart at that end of the aligning device which is nearer the casting-carriage 60 so as to be at similar levels to the slots in the casting-carriage. In this arrangement, the guide slots may converge together at or towards the other end of the aligning device so that the junction point is at a level 65 substantially midway of the uppermost slots in the casting-carriage.

The lowermost position of the elevator is arranged so that the matrix carrying member thereof is located horizontally opposite the said junction point. It will be appreciated that with this arrangement the matrices at a higher level will move downwards and the matrices at a lower level will move upwards and all the matrices are transferred to an elevator at a level between the lower and upper levels in the casting-carriage. With this arrangement the maximum inclination of the guideways is considerably less than when the matrices are conveyed 80 either to the highest or lowest levels. The following is a description of two constructions according to this invention, one of which may be used for two-letter matrices and the other may be used for three-letter 85 matrices. 90

Reference is made to the accompanying drawing in which:

Figure 1 shows the casting-carriage in its uppermost position, the elevator in its lowermost position and the aligning device between these two parts. 95

Figure 2 shows the matrices and spacer bars on their way through the aligning device for the two-letter matrices. 100

Figure 3 is a cross-section on the line A—B of Figure 2, and

Figure 4 is a diagrammatic illustration of the aligning device for the three-letter matrices. 105

The casting-carriage 1 is provided with four horizontal parallel slots 2, 3, 2^a and 3^a for engaging the upper and lower ears of the matrices. The distance between the slots 2 and 3 or between 2^a and 3^a corresponds, as is usual, to the distance between the two letters or intaglio representations. 110

on the edge of the matrix. The elevator 4 which transfers the matrices to the distributor has a single slot 5 which engages the upper ears of the matrices.

5 A plate member 6 which constitutes the aligning device is secured to the frame of the machine between the uppermost position of the casting-carriage and the lowermost position of the second elevator. The said 10 plate member comprises two plates vertically disposed and having their faces spaced apart parallel and opposed to one another. Each plate has formed on its inner face inclined slots 2^b, 3^b and 2^d, 3^d, which at the 15 casting-carriage side of the plate are spaced apart so as to be at the same level as the corresponding slots in the casting-carriage. The slots 2^b, 3^b converge together into a single slot 5^b which is arranged at an intermediate level to the slots 2 and 3. The 20 slots 2^d and 3^d converge together into a single slot 5^d which is at a level intermediate of 2^a and 3^a.

When the casting-carriage reaches its uppermost level, Figures 1 and 2, the line of 25 matrices is transferred from the carriage to the elevator through the stationary plate member 6. The upper and lower ears of the matrices leave the slots 2, 3 and 2^a, 3^a 30 and pass into the inclined slots 2^b, 3^b and 2^d, 3^d of the plate member 6, whereby the matrices are brought to a single level, at which level the upper ears are guided into the slot 5 of the elevator. Figure 4 shows 35 a casting-carriage arranged for accommodating three-letter matrices and the arrangement of slots in the aligning device for bringing the matrices to a single intermediate level.

40 I claim:—

1. A matrix aligning device for use in a matrix-setting and line-casting machine having a number of tracks along any of which each matrix may be traversed, which 45 aligning device is to be arranged in line with the tracks and comprises a guideway having a plurality of guide slots corresponding in number to the number of tracks, and so spaced apart at one end of the guideway 50 as to constitute extensions of the tracks, which slots converge together towards the other end of the guideway at a junction point situated intermediate of the outermost lines along which the matrices travel 55 when leaving the said tracks.

2. In a matrix-setting and line-casting machine having a number of tracks along

any of which each matrix may be traversed and comprising a vertically movable casting-carriage and an elevator, the combination with the casting-carriage and elevator, of an aligning device comprising a guideway situated between the uppermost position of the casting-carriage of the machine and the lowermost position of the elevator, and having a number of guide slots spaced apart at that end of the aligning device which is nearer the casting-carriage so as to be at similar levels to the slots in the casting-carriage, which guide-slots so converge together towards the other end of the aligning device that the junction point is at a level substantially midway between the outermost slots in the casting-carriage, a matrix carrying member of which elevator is located horizontally opposite said junction point when the elevator is in its lowest position.

3. A matrix aligning device for use in a matrix-setting and line-casting machine 80 having a number of tracks along any of which each matrix may be traversed, which aligning device comprises two vertical plates spaced apart, situated parallel and opposed to one another, and having a set 85 of slots formed in each of the opposed faces, which slots in each face are so spaced apart at one end of the face as to constitute extensions of the tracks and converge together towards the other end of the face 90 at a junction point intermediate of the outermost lines along which the matrices travel when leaving the said tracks.

4. A matrix aligning device for use in a matrix-setting and line-casting machine 95 having a number of tracks along any of which each matrix may be traversed, which aligning device is to be arranged in line with the tracks comprises a guideway having two sets of guide slots so spaced apart 100 that one set will co-operate with the upper ears of each matrix and the other set with the lower ears of each matrix, the guide slots in each set being so spaced apart at one end of the guideway as to constitute extensions of the tracks and converge together towards the other end of the guideway at a junction point intermediate of the outermost lines along which the matrices travel when leaving the said tracks.

110 In testimony whereof I affix my signature.

KARL RÖGER
